(57) **CLAIM**

The ornamental design for a hair dryer, as shown and described.

DESCRIPTION

FIG. 1 is a perspective view of a hair dryer showing a new design.

FIG. 2 is a front view thereof.

FIG. 3 is a rear side view thereof.

FIG. 4 is a left side view thereof.

FIG. 5 is a right side view thereof.

FIG. 6 is a top plan view thereof.

FIG. 7 is a bottom plan view thereof; and,

FIG. 8 is another perspective view from the rear and bottom side thereof.

The broken lines in the drawings depict portions of the hair dryer that form no part of the claimed design.
